UNITED STATES PATENT OFFICE

MICHAEL SPECIALE, OF NEW YORK, N. Y.

CLOCK

Application filed October 18, 1928. Serial No. 400,631.

This invention relates to clocks.

It is among the prime objects of the present invention to provide a clock having a plurality of hour hands adapted to indicate various time differences.

It is a further object of the present invention to provide a clock having a twenty-four-hour dial. The hour points are divided to indicate minutes, whereby an hour hand will 10 denote the hours and the minutes, thus rendering it unnecessary to have a separate minute hand.

A further object of the present invention is to provide a clock with a plurality of hour 15 hands, frictionally engaging the same arbor, whereby they may be adjusted and move simultaneously with each other to indicate time differences.

Other objects of the present invention include the novel and improved structure for 20 the engagement of the hands upon the arbor.

Numerous other objects and features of the present invention will be apparent from a 25 consideration of the following specification taken in conjunction with the accompanying drawings, in which

Figure 1 is a plan view of one embodiment of the present invention;

Fig. 2 is a detail sectional view taken on 30 the lines 2—2 of Fig. 1;

Fig. 3 is a detail side elevation of one of the hands, and

Fig. 4 is a rear elevation of one of the hands.

Referring more particularly to Fig. 1 of the drawings, the present clock includes a face divided into twenty-four hour spaces, the hours being indicated by the large numerals 10 on the face. Between each of the hour numerals, the face is divided in a suitable manner to indicate minute fractions of an hour. For instance, in illustrating, the marks denote every five-minute interval between the hour intervals, as indicated by the numeral 11. It will be understood that any desired arrangement of markings and the numerals therefor, may be provided.

The face further includes a central band 12, one side of which is white and indicates 50 that that side of the face is for A. M. time,

while the opposite side is black and indicates P. M. time. The face further includes suitable indicia for designating the times. It is, however, understood that the invention is not confined to the specific marking of the twenty-four hour dial herein indicated, but that such markings may be varied without departing from the spirit of the invention. It will further be understood that the clock and clock mechanism may be of any desired type, such as mechanical or electrical, and the invention is not confined to any preferred type of such movement, it being obvious that the use of a pendulum or spring in mechanical train or specific types of electrical clock mechanism, does not depart from the spirit or scope of the invention.

By the provision of the minute divisions between the indicated hours on the face of the clock, it will readily be seen that the conventional minute hand is not required. Thus the white outside time hand of Fig. 1 of the drawings, indicates thirty minutes past eleven o'clock A. M. time without requiring the use of an independent minute hand. Thus a single arbor, indicated by the numeral 14, is provided, which extends centrally through the face and which is turned by suitable mechanism as an hour hand arbor.

Referring more particularly to Fig. 2 of the drawings, it will be seen that the arbor 14 may be associated through the hour gears 15, with any desired type of clock train. The arbor 14 extends through the face of the clock and includes an inner shoulder 16, recessed as at 17, together with an outer shoulder 18, recessed as at 19.

It will readily be seen that as but a single arbor is used in the present invention, the clock train may be materially simplified and the usual minute arbor and minute train is not required, thus the elimination provides novel simplicity in the device.

The clock further includes a pair of removable frictionally engaged hands 20 and 21. The outer hand 20 is adapted to indicate local time, as shown by its indicia, while the inner hand 21 is adapted to show outside time and includes a rearwardly extending portion

22 which bears indicia so indicating. The inner hand 21 includes a sleeve 23, which fits over the larger shoulder 16 and further includes a pair of spring fingers 24, the fingers 24 having forwardly extending ends 25 which pass on each side of the hand to be operable from the front, as will be herein-after described. Intermediate the ends of the fingers 24, they are received in a recess 17, thus locking the hand in position on the arbor, whereby it frictionally engages the arbor and rotates therewith.

The outer hand 20 includes a sleeve 26, which surrounds the shoulder 18 and is provided with fingers 27, which are received in the recess 19 to lock the fingers in frictional engagement with the arbor 14. The ends of the fingers 27 extend forwardly, as at 28, to provide operating terminals therefor. The sleeves 23 and 26 have side apertures 29, through which the fingers 24 and 27 pass for engagement in the recesses 17 and 19. The hand structure in combination with the arbor structure, is such that by extending outwardly the fingers, they are removed from the recesses and the hand can be taken off the arbor. When in position, however, it will be seen that the hands may be manually set, but that the spring engagement of the fingers is such 30 as to provide for rotation of the hands with the arbor. The base of the hands also includes counterbalance weights 30, which balance the weight of the hand and provide a balance for the energy required by the arbor 35 to turn the hand, it being understood that the counterbalance is not sufficient to move the hand with respect to the arbor or to retain the hand against movement with respect to the arbor.

40 In the operation of the device, the outer local time hand 20 is set at local time, and the outside time hand is adjusted to a position adapted to show outside time at the desired place. A suitable chart preferably accompanies the clock to indicate time differences between various places. Thus the device may be used, for instance, in conjunction with daylight saving time, in which the hand 20 is set for standard time, while the outside time 45 hand is set one hour in advance to indicate daylight saving time. After setting the hands, it will be seen that their frictional engagement with the arbor provides for the rotation of both hands in unison in response to the clock train. It will readily be seen that the hands may be arranged to indicate international time by setting the outside time hand in advance or behind the local time hand in accordance with the chart provided, 50 whereby time in various countries may be indicated by the outside time hand as it moves simultaneously with the local time hand.

55 It will be seen that the clock may be used for family or office as a common clock for local time only, by using one hand or both—

marking the same local time. This clock is particularly useful on trains in connection with railroad stations, on ships, and steamship offices, naval observatories, telegraph offices, airplanes and airports, broadcast stations or the like, where it is necessary to know the local time as well as outside time.

70 From the foregoing it will be seen that the present invention provides a device adapted to simultaneously indicate time in various places. It will therefore be seen that the invention provides a novel twenty-four-hour clock which does not require a minute hand. Thus a clock mechanism may be considerably simplified. It will be understood that the invention is not specifically confined to the details herein shown but that numerous changes, modifications, and the full use of equivalents may be resorted to without departing from the spirit or scope of the invention as outlined in the appended claim.
